UNITED STATES PATENT OFFICE

JAMES A. ANDREWS, OF AUGUSTA, MAINE

SUPPORT FOR CLEARER ROLLS

Application filed March 4, 1931. Serial No. 519,978.

This invention relates to certain new and useful improvements in supports for clearer rolls and more specifically comprehends a support which allows of movement of the roll so as to compensate for any variations in the roll diameter due to the roll picking up lint or other matter. These rolls frequently pick up lint from the drawn-in yarn or sliver, which increases the roll diameter, and generally in spots, the present invention aiming to provide means accordingly to meet this situation.

A further object of the invention is to provide a novel means whereby a clearer roll may be detachably mounted between the drawing-in and intermediate sets of rolls in a spinning machine of the long draught type.

A further object of the invention is to so mount the clearer roll as to permit limited forward and rearward movement and also vertical relative to the stationary sets of rolls.

A still further object of the invention is to balance the supporting means so that the clearer rolls will be allowed free movement and thus increase the efficiency of their operation. Further objects and advantages will become apparent as the description proceeds, reference being had to the accompanying drawing in which;

Figure 1 is a perspective view of the supporting clip;

Figure 2 is a fragmentary perspective view of the clearer roll;

Figure 3 is an elevation of the clasp and roll in operative assembly showing in dotted lines the action of the clip upon movement of the roll; and

Figure 4 is a fragmentary plan assembly showing the roll and clip in operative position.

In proceeding in accordance with the present invention, a clearer roll 1 is shown which is mounted as shown in Figure 4 below and between the drawing in rolls A and the intermediate rolls B of a spinning machine of the long draught structure. The clearer roll 1 has portions of its surface cut away to form a cylindrical neck or axle, 2. These reduced portions or necks 2 occur at points which are

in registry with the portion of the stationary rolls which are not used in the attenuation of the yarn.

For the purpose of supporting the clearer rolls in the desired relation to the rolls A and B, spring clips 3 are provided. These clips consist of a U-shaped saddle 4 carrying a weight 5 on one end and having a shelf like 6 extension on the other, the latter having an upturned lip 7 at its free end. The saddle or bight of the U is of substantially the same width as, the space between the adjacent drawing in rolls A—A and conformably seats upon the part A' of the shaft of the rolls so that no movement axially of its support may be had when the clip is in position. The extension 6 serves as a bearing surface for the neck 2 of the clearer roll and, by virtue of its upturned end or lip 7 allows a certain freedom of motion to the clearer roll 1 backward and forward with relation to the rolls A and B. The weight 5 is secured to the body of the clip by the insertion of screw head 8 in the slot 9 which latter has its upper end enlarged to a greater diameter than that of the screw head 8, so that the clip may be removed, and applied without complete removal of the screw.

A lubricant passage 10 is provided to enable lubricant to be supplied therethrough to reduce the frictional resistance between the shaft of rolls A and the clips 3.

In operation, the clips 3 are placed over the shaft carrying the drawing-in rolls so as to be supported thereby and the clearer roll 1 is positioned so that its surface contacts rolls A and B and its neck portions engage the shelves 6 of the clips 3. When the machine is running the clearer roll may accordingly move forward or backward or vertically due to the presence of lint or due to the difference in speed of rolls A and B, thereby affording uniformity of its action.

Having thus described my invention what I claim as new and desire to secure by Letters Patent is:

1. In combination with the drawing-in and intermediate rolls of a spinning machine, a clearer roll underlying and contacting both the drawing-in and intermediate rolls, said

- clearer roll having a portion of greatly reduced diameter intermediate its ends and in registry with the unused portions of the drawing-in roll, a spring bearing clip carried by the axle of the drawing-in roll and having a shelf like projection for engagement with the axle of said clearer roll to support the same, said shelf having an upturned outer end which acts in conjunction with the body 5 of the clip to limit the movement of the clearer roll to the confines of the shelf and a weight carried by the other end of the clip whereby the weight of the roll will be balanced.
- 10 2. In combination with a shaft having spaced drawing-in rolls, and the intermediate rolls of a spinning machine, a clearer roll underlying and contacting the drawing-in and intermediate rolls and having a reduced part 15 and a clip member having a part mounted on the shaft of and in the space between the drawing-in rolls so as to be solely supported by and for swinging movements on said shaft, a seat carried by said member and of greater 20 length than and receiving said reduced part of the clearer roll to support the latter for movement lengthwise of the seat, and counterbalancing means connected to the member.
- 25 3. In combination with a shaft having spaced drawing-in rolls, and the intermediate rolls of a spinning machine, a clearer roll underlying and contacting the drawing-in and intermediate rolls and having a reduced part 30 and a clip member having a part mounted on the shaft of and in the space between the drawing-in rolls for swinging movements on said shaft, means for mounting the reduced part of the clearer roll on the member for bodily movement lengthwise of the last 35 named means, and counterbalancing means connected to the member.
- 40 4. In combination with a shaft having spaced drawing-in rolls, and the intermediate rolls of a spinning machine, a clearer roll 45 underlying and contacting the drawing-in and intermediate rolls and having a reduced part and a strip-like member having a part mounted on the shaft of and in the space between the drawing-in rolls so as to be solely 50 supported by and for swinging movements on said shaft, a seat carried by said member and receiving said reduced part of the clearer roll to support same, for limited bodily movement lengthwise of the seat, and counterbalancing means connected to the member.
- 55 5. In combination with a shaft having drawing-in rolls and the intermediate rolls of a spinning machine, a spring clip of substantially U-shape having its bight received 60 on the top of the shaft of the drawing-in rolls, a clearer roll underlying and contacting the drawing-in and intermediate rolls, holding means carried by and extending outwardly from one end of the clip for supporting 65 the clearer roll for bodily movement

lengthwise of the holding means, and counterbalancing means connected to the outer face of the opposite end of the clip.

In testimony whereof I have signed my name to this specification.

JAMES A. ANDREWS.
